KEY ACTION FOR TYPEWRITING AND OTHER KEY-OPERATING MACHINES.

Application filed September 8, 1925. Serial No. 55,227.

My invention relates to key-action for typewriters and other type bar and key operating machines, actuating means at all times being operatively connecting the type bar and key lever, moving the type bar to printing point upon the depression of a key lever and means reversely breaking the said connection after the printing impact of the type bar for the return of the type bar to normal position 5 while the key lever is in depressed position; this broad object being the subject matter of an application filed by me on November 5th, 1923, Serial No. 672,871, which issued as Patent 1,643,203 September 20, 1927, as a continuation in part of previous devices comprising a detachable connection or gap at some point between the key lever and type bar after the latter has been given the movement necessary to effect the printing and 20 before the key lever has completed its movement.

A specific object of the present invention is to provide means of the character specified above with which in the main is in the nature 25 of another form of structure that may readily be incorporated in certain typewriting machines, wherein actuating means at all times operatively connect the type bar and the key lever with only slight modification of structural features of said machines as they now exist. I have shown my invention embodied, in the present instant, in the L. C. Smith Brothers standard machine, and in which the 30 invention may be readily incorporated by slight modification of structural features of the machine in effecting such incorporation. It should be understood, however, that the 35 invention is not restricted to use in a machine of this type, but may be employed 40 wherever found available.

The desired principle of operation, new mechanical function, operative expedients, and other objects and advantages will, hereinafter be described in the following disclosure, and will be more particularly pointed out in the appending claims. In the accompanying drawings, wherein like reference characters indicate corresponding parts in the various views—

50 In the drawings Figure I, is a vertical section of a typewriting machine, one key-action only being shown in normal position; Fig. II represents a view of the key mechanism similar to Fig. I, the key lever being shown in a

depressed position and responding the type 55 bar. Fig. III, also is a key mechanism similar to Fig. I, the key lever being shown in a depressed position and the type bar returned to its initial position. Fig. IV is a skeleton view of the key mechanism for illustrative purposes in describing the mode of operation of machine shown. Fig. V is a cross section of certain parts of my invention. It is understood, of course, that for the sake of clearness and to avoid complication of 60 drawings the applicant has omitted to show or describe the remainder of key levers and type bars as well as other devices necessary or advisable in the complete machine.

In the embodiment in Fig. I, 1 indicates 70 the frame of the typewriter, 1^a indicates the front and 1^b the rear, having a power driven paper carriage 2 supported in the rear on guide rod 3 and in front on guide rod 4 the principal parts of the carriage not being 75 shown in the drawing; 5 indicates the common platen carried by paper carriage 2; 6 indicates one of the usual type bars carrying type 7 at its front end, and having an eccentric pivot 8 at the heel of rear end, and is 80 arranged to turn on pivot 9 in the form of a segment basket disposed vertically below frame face of the plate; 10 and 10^a Fig. I indicating part of the basket frame subjecting the type bar 6 to "basket shift," thereby 85 providing the type 7 with a common printing point A, as the type bar 6 turns on pivot 9 from the normal horizontal position of the rest on the segment 11; 12 indicates one of the key levers carrying at the front end finger 90 key 13, the rear end pivoted at 14 to bar 14^a in the rear of the machine, and is kept normally in its elevated position by return spring 15 supported by bar 15^a at normal rest of key lever bearing against the under side of stop 95 bar 15^b above the front part of the key lever 12, in the usual manner.

Key lever 12 is formed with an upward projection 16 and provides a saddle-backed seat 17 for the trip link coupling hereinafter 100 described. The key lever 12 is described as having two incidents of operation, namely; the incident of depression and incident of release. The incident of depression is disclosed by the downward movement of key 105 lever 12 from radius B to radius C, and the incident of release is disclosed by the upward movement of key lever 12 back from radius

C to radius B. The type bar 6 is described as having two incidents of operation, namely, the incident of response and the incident of recoil. The incident of response of type bar 6 is disclosed by the movement of the type bar from its initial rest radius E to the printing point A, indicated by radius F, forming arc G from pivot 9. The incident of recoil of type bar 6 is disclosed by its movement from its printing point A back to normal rest E. These incidents of operation are, of course, present in previous type bar action in so far as the incident of response E to A of the type bar 6 occurs simultaneously with the incident of depression B to C, of key lever 12, and the incident of recoil, A to E, of the type bar occurs simultaneously with the incident of release C to B, of the key lever, but my invention relates to a later correlation of incidents of operation of the key levers with that of the type bar, in conforming to the operative expedient by which both the incident of response, E to A, of the type bar and incident of recoil, A to E, occur during the one incident of depression, B to C, of the key lever.

In this case, a novel form of trip link coupling peculiarly arranged between the key lever and the type bar accomplishes this operative expedient; the form, action and arrangement of said trip link coupling being the subject matter of this application, hereinafter described.

18 indicates one of a series of vertically disposed vibratory levers corresponding in number with type bars 6 and key levers 12. Intermediately their ends, the vibratory levers 18 are pivoted at 19 in a bar 20 extending across the machine, and each at its upper end is pivoted at 21 as usual to a backward pull link 21^a which engages the type bar at pivot 8.

22 and 23 are two links of what is described as a trip link coupling, which by way of connecting lever 18 and backward pull link 21 at all times operatively connect the type bar and key lever.

The upward curved draw link 22 is pivoted at 25 to the lower ends of the vibratory lever 18, and the front end of the upward curved draw link 22 is pivoted at 24 to the front end of the thrust link 23, the rear end of the thrust link 23 being pivoted at 26 to the upward projection 16 of the key lever 12.

The relative normal position of pivots 24, 25 and 26 are engaged in a line nearly horizontal with the key lever 12 as shown by J J Fig. IV, disclosing the trip link coupling to be horizontally disposed as distinguished from being engaged perpendicular to the key lever. It will be observed that the upward curved draw link 22 and the thrust link 23, constituting the trip link coupling, operate in a plane above the key lever, disclosing the invention to be overslung. Also, it will be noted that the upward curved draw links 22

and thrust link 23 operate in front of the vibratory lever 18 disclosing the trip link coupling to forwardly engaged.

27 is a return spring, front end engaging the hole 27^a in the rear end of the upward curved draw link 22 and the rear end of return spring 27 engaging one of the plurality of holes 27^b in plate 30 hereinafter described. When the front end of the return spring 27 is pulled forward and upward the rear end moves downward and serves to rock the upward curved draw link 22 on pivot 25 and to hold the vibratory lever 18 normally in position shown in Fig. I and to return it and the type bar 6 to normal position E after operation.

While the upward curved draw link 22 and the thrust link 23 are operating under tension lock, both ends of return spring 27 move in opposition and are drawn to high tension, and then at this stage, the energy is diverted to recoil of the type bar as thrust link 23 is tripped out of tension lock.

28 is an extended nose of the upward curved draw link 22 and is designated as a fulcrum trip nose, pivot 24 being the fulcrum point about which the upward curved draw link 22 turns in cooperating with the saddle-backed seat 17 on top of key lever 12 in lifting thrust link 23 out of responsive tension lock and cooperating with return rod 29 in restoring the coupling to normal operative position during the incident of the release of the key lever.

The mechanical movements and operation thereof are the important factors in providing the function of the key action. A further description of the operative principles therefore follows: The geometric circle H H Fig. IV, with a horizontal diametrical line J J, from the forward border pivot 24 to

backward border pivot 25 circumscribes what is termed the actuating plane. The horizontal diametrical line J J crossing the actuating plane, from the forward border pivot 24 to the backward border pivot 25 indicates the divert tension line and divides the actuating plane into an upper zone of response K and a lower zone of reaction L; the upper zone of response K having to do with the response of the type bar 6 from radius E to radius F as the key lever 12 is being depressed from radius B to radius D; and the lower zone of reaction L having to do with the recoil of the type bar 6 from the printing point A to radius E at rest as the key lever 12 is being continually depressed from radius D to radius C of depression. The normal or idle position of the upward curved draw link 22 operates in the upper zone of response K as shown in Figures I, II, III, IV. And thrust link 23 operates within the forward radius of the actuating plane. It is necessary that the upward curved draw link 22 and thrust link 23 be relatively major and minor in

length and link 23 be in such form and so engaged in hinge-fold fashion so as to permit the interior pivot 26 to oscillate between the forward border pivot 24 and backward border pivot 25 in crossing and recrossing the horizontal divert tension line J-J. In this case, the elements 22 and 23 of the trip link coupling are folded during the incident of depression from radius B to radius D of the key lever 12 and simultaneously with the incident of response of the type bar 6 from radius E to printing point A; and the hinge-fold elements 22 and 23 unfold during the remainder of depression, radius D to radius C of key lever 12 simultaneously with the recoil of the type bar 6 from printing point A back to radius E.

The saddle-backed seat 17 provided by the key lever 12 stops the forward border pivot 24 and effects responsive tension lock of trip link 23 under influence of return spring 27 as the key lever 12 is being depressed from radius B to radius D. This tension lock of thrust link 23 is also described as contractive tension lock meaning that while the key lever 12 is being depressed, the energy required to respond the type bar 6 effects contractive pressure or thrust from the interior pivot 26 to the forward border pivot 24 instead of expansive tension or pull. The contractive tension of thrust link 23 stops its oscillation and is moved bodily edgewise downward with the key lever 12, as shown in Fig. II, until the interior pivot 26 crosses the horizontal divert tension line J-J into the zone of reaction L. Simultaneously with contractive tension lock of thrust link 23, upward curved draw link 22 operates under expansive tension between the forward border pivot 24 and the backward border pivot 25 while the key lever 12 is being depressed from radius B to radius D to respond the type bar 6 from radius E to printing point A, and the expansive tension of link 22 being relaxed while the key lever continues the incident of depression from radius D to radius C and simultaneously with the recoil of the type bar 6 from the printing point A to radius of rest E.

By change in relative positions of the forward border pivot 24 and the backward border pivot 25 the interior pivot 26 is brought down within the lower zone of reaction L thereby releasing the contractive tension lock of thrust link 23. The release of contractive tension-lock of thrust link 23 permits it to resume oscillation reversely breaking the coupling about the time the type impacts the printing point A. When the trip link coupling reversely breaks in the above manner there being no further obstruction to the recoil of the type bar 6, it immediately recoils from A to E while the key lever 12 continues its incident of depression from D to C and contacting with stop bar 34.

65 The dotted line M M indicates the correla-

tive relationship of the border pivots 24 and 25 and the interior pivot 26 during the process of operation, viz: Dotted line M M Fig. I shows where the tri-pivotal relationship of pivots 24, 25 and 26 forms obtuse angle at 70 the interior pivot 26 pointing upward within the upper zone of response during the normal position and effecting response of the type bar during the depression of the key lever 12. Dotted line M M Fig. II shows about a 75 45° alignment of the border pivots 24 and 25 and the interior pivot 26 at the time the type bar completes its response or impact and begins to recoil. Dotted line M M, Fig. III shows an obtuse angle, at the interior pivot 80 26 formed by the tri-pivotal relationship, pointing downward within the zone of reaction L as the type bar 6 recoils.

Inherent to the common key action whenever certain keys are accidentally and slightly depressed part way down they suspend their respective type bars along the type arc G interfering with the response and recoil of intentionally struck keys, but the present invention provides the exigency that when the finger key 13 is slowly depressed, the type bar 6 responds to the degree on arc G corresponding to the radius of depression of the key lever 12 and from there automatically recoils without impact with the platen. This is an inherent exigency of my invention referred to as the operative expedient by which type bars responding to slowly depressed keys part way down automatically recoils without interfering with responding type, hence the name "automatic type bar recoil mechanism" or "automatic coupling". This operative expedient is accomplished by a trippet plate 30 with trip hammer 30^a. Intermediately its ends the trippet plate is pivoted at 31 on the side of the key lever 12, in the rear of thrust link 23 and is provided with a slot 32 engaging pivot 31 which permits the trippet plate 30 to vibrate independently and in opposite movement of key lever 12. The downward movement of the trip hammer 30^a is limited by the stop bar 34 engaged at the incident of depression of key lever 12, causing the trippet plate 30 to turn on pivot 31 and the forward end 30^a to impact with pivotal point 24 of thrust link 23. Trippet plate 30 is provided with angle top 30^b Fig. V held in normal position on top of key lever 12 by return spring 27. The rear end of the upward curved draw link 22 sustains a frictionless wheel 22^a communicating with the angle top 30^b of trippet plate 30 in returning the coupling to normal operative position upon release of the key lever 12. The trip hammer 30^a is wider than the key lever at the saddle-backed seat 17, and the fulcrum trip nose 28 is as thick as both the key lever and the trip hammer hence the upper edge 30^b of the trip hammer engages the fulcrum trip nose 28 and trips the trip link 130

coupling out of operative tension lock about the time the key lever is depressed part way between radius B and radius C of incident of depression of key lever 12, and when the key lever is slowly depressed, the type bar having no momentum it drops back without printing impact. Variations may be resorted to within the scope of the invention, and portions of the improvement may be used with 10 out others.

What I claim as new and desire to secure by Letters Patent, is:

1. In a typewriting machine, a type bar, a key lever, actuating means at all times operatively connecting the type bar and key lever comprising a backward pull link, a vibratory lever, a reversely breaking actuating connection operatively connecting the key lever and vibratory lever for moving the type bar to the printing point upon depression of the key lever, means reversely breaking said connection after the printing impact to return the type bar to normal position while the key lever is in depressed position, means 25 restoring said connection to normal operative position upon release of the key lever.

2. In a typewriter machine, a type bar, a key lever, actuating means at all times operatively connecting the type and key lever comprising a backward pull link pivoted to the type bar, a vertically disposed vibratory lever pivoted to the backward pull link, a trip link coupling pivotally connecting said key lever and vibratory lever for moving said type bar 35 to printing point upon depression of the key lever, means reversely breaking said coupling after printing impact of the type bar for returning the type bar to normal position while the key lever is in depressed position, means 40 restoring said coupling to normal operative position upon release of the key lever.

3. In a typewriting machine, a type bar, a key lever, actuating means at all times operatively connecting said type bar and key lever 45 comprising a backward pull link connected to the type bar, a vertically disposed vibratory lever, a pivotal rod for said vertically disposed vibratory lever intermediately of its ends, a trip link coupling comprising an upward curved draw link and a thrust link at all times operatively connecting said key lever and vibratory lever for moving the type bar to the printing point upon depression of the key lever, means actuating said coupling 55 to return the type bar after the printing impact while the key lever is in depressed position, means restoring said coupling to normal operative position upon release of the key lever.

60 4. In combination, a type bar, a key lever, a segmental pivot rod therefor, actuating means at all times operatively connecting said key lever and type bar comprising a backward pull link, a vertically disposed vibratory lever, a trip link pivoted intermediately of its ends, a trip

link coupling comprising an upward curved draw link connected to the vibratory lever, a thrust link pivoted to said key lever intermediately of the ends of the latter and connected to said draw link—moving the type bar to printing point upon depression of the key lever, means reversely breaking said coupling after printing impact of the type bar, means returning the type bar to normal position while key lever is in depressed position, means restoring said coupling to normal operative position upon release of the key lever. 75

5. In a key action for a typewriting machine, a type bar, a segmental pivot rod therefor, a key lever, actuating means at all times operatively connecting said key lever and type bar comprising a backward pull link operatively connected to said type bar, a vertically disposed vibratory lever with upper end pivoted to said backward pull link, an upward curved draw link operatively connected to said vibratory lever, a thrust link operatively connecting the upward curved draw link and key lever, moving the type bar to printing point upon depression of the key lever, means reversely breaking said coupling after printing impact of the type bar for return of the latter to normal position while key lever is in depressed position, means restoring said coupling to normal operative position upon release of the key lever. 90

6. In a key action for key-operating machine, a key lever, a type bar, a backward pull link connected to the type bar, an upward curved draw link, a vertically disposed vibratory lever connected to the upward curved draw link, a thrust link connected to the key lever, a forward border pivot of an actuating plane connecting said thrust link and draw link, a saddle-backed seat provided by the top of the key lever for said forward border pivotal point moving the type bar to printing point upon depression of the key lever, means tripping said forward border pivotal point out of the saddle-backed seat reversely breaking said coupling after printing impact of the type bar for returning the type bar to normal position while key lever is in depressed position, means restoring said forward border pivotal point to the saddle-backed seat upon release of said key lever. 105

7. In a type key action, a type bar, a key lever having an upward projection intermediately of its ends, actuating means at all times operatively connecting said key lever and type bar comprising a backward pull link, a vertically disposed vibratory lever, a trip link coupling comprising an upward curved draw link and a thrust link pivoted to said upward projection provided by the key lever moving the type bar to printing point upon depression of the key lever, means reversely breaking said coupling after printing impact of the type bar, means for the 110 115 120 125 130

return of the type bar to normal position while key lever is in depressed position, means restoring said coupling to normal operative position upon release of the key lever.

5 8. In a type key mechanism, a type bar, a key lever, an upward projection provided by the key lever; a saddle-backed seat in front of said upward projection; actuating means at all times connecting said type bar and key lever comprising a backward pull link, an upward curved draw link, a vertically disposed vibratory lever pivotally operated by the upward curved draw link, a thrust link pivoted to the upward projection of the key lever and riding the saddle-backed seat moving the type bar to printing point upon depression of the key lever, means returning the type bar to printing point upon depression of the key lever, means reversely breaking said coupling after printing impact of the type bar, means returning the type bar to normal position while key lever is in depressed position, means restoring said coupling to normal operative position upon release of the key lever.

9. In a type key action mechanism, a key lever, a type bar, actuating means at all times operatively connecting the key lever and type bar comprising a backward pull link, an upward curved draw link, a vertically disposed vibratory lever extending upwardly and downwardly from its pivot and connecting said draw link and backward pull link, a thrust link connecting said upward curved draw link and key lever moving bodily downward with said key lever upon depression of the latter responding the type bar to printing point, means limiting the downward movement of the forward end of said thrust link reversely breaking said coupling after the printing impact of the type bar for returning the latter to normal position while key lever is in depressed position, means for restoring the thrust link to normal operative position upon release of the key lever.

10. In a type key mechanism, a type bar, a key lever, an upward projection thereof, actuating means at all times operatively connecting the key lever and type bar comprising a backward pull link, a vertically disposed vibratory lever, a trip link coupling horizontally disposed and engaged above the key lever forwardly of said vibratory lever, a forward border pivot of an actuating plane connecting the said upward curved draw link and thrust link above the key lever, a backward border pivot of the actuating plane connecting the upward curved draw link and vertically disposed vibratory link above the key lever, an interior pivot of the actuating plane connecting the rear end of the thrust link and upward projection of the key lever, said elements moving the type bar to printing point upon depression of key lever, means reversely breaking said elements after print-

ing impact of the type bar returning the type bar to normal position while key lever is in depressed position, means restoring said elements to normal operative position upon release of the key lever.

11. In a typewriting machine, a type bar, a key lever, an upward projection thereof, actuating means at all times operatively connecting said type bar and key lever comprising a backward pull link, a vertically disposed vibratory lever, a trip link coupling comprising a relatively long upward curved draw link and a relatively short thrust link pivoted to the upward projection of the key lever and normally operating within the concave of said draw link moving the type bar to the printing point upon depression of the key lever, means tripping said thrust link out of the concave of said upward curved draw link reversely breaking said coupling after the printing impact of the type bar for returning the type bar to normal position while the key lever is in depressed position, means restoring said thrust link to its normal operative position within the concave of said upward curved draw link upon release of the key lever.

12. In a typewriter key action, a type bar, a key lever, actuating means at all times operatively connecting said type bar and key lever comprising a backward pull link, a vertically disposed vibratory lever an upward curved draw link operating in an upper zone of an actuating plane, a thrust link operating within the forward radius of an actuating plane, a backward border pivot connecting said draw link and vibratory lever at the backward border of an actuating plane, a forward border pivot connecting said thrust link and draw link at the forward border of said actuating plane, an interior pivot of the actuating plane connecting said draw link and key lever normally in a zone of response moving the type bar to printing point upon depression of the key lever, means actuating the interior pivot downward across a divert tension line between the forward border pivot and the backward border pivot breaking reversely said mechanism after the printing impact of the type bar for returning the type bar to normal position while the key lever is in depressed position, means restoring the interior pivot to its normal operative position within the upper zone of response upon release of the key lever.

13. In a key action for a typewriting machine, a type bar, a key lever, actuating means at all times operatively connecting said type bar and key lever comprising a vertically disposed vibratory lever, a backward pull link operatively connecting the vibratory lever and type bar, a trip link coupling comprising an upward curved draw link and a thrust link operatively connecting the vi-

bratory lever and key lever moving the type bar to printing point upon depression of the key lever, a fulcrum trip nose provided by the forward end of the upward curved draw link, a saddle backed seat provided by the key lever cooperating with said fulcrum trip nose reversely breaking said coupling after the printing impact of the type bar, a return bar extending across the machine above the key lever cooperating with the fulcrum trip nose after the recoil of the type bar, restoring said coupling to normal operative position upon release of the key lever.

14. In a typewriting machine, a type bar, a key lever, actuating means at all times operatively connecting the type bar and the key lever comprising a backward pull link, a vertically disposed vibratory lever, a thrust link pivoted to the key lever, an upward curved draw link pivoted intermediately of its ends to the lower end of said vibratory lever and its forward end pivoted to the front end of said thrust link moving the type bar to printing point upon depression of the key lever, means reversely breaking said coupling after printing impact of the type bar returning the latter to normal position while the key lever is in depressed position, an angle top trippet plate communicating with the upper edge of said key lever for holding said trippet plate in normal position, a frictionless wheel carried by the rear end of said upward curved draw link communicating with the angle top trippet plate restoring said coupling to normal operative position upon release of the key lever.

15. In a mechanical movement for a typewriter key, a type bar, a key lever, a backward pull link operatively connected to the type bar, a vertically disposed vibratory lever operatively connected to the backward pull link, elements of a trip link coupling comprising an upward curved draw link and a thrust link, a forward border pivot of an actuating plane connecting the forward end of the upward curved draw link and the forward end of the thrust link above the key lever, an interior pivot connecting the thrust link to the side of the key lever interior of the actuating plane and within an upward zone of response during normal position of said coupling, a backward border pivot of the actuating plane connecting the upward curved draw link and vibratory lever moving the type bar to printing point upon depression of the key lever, means reversely breaking said coupling after the printing impact of the type bar returning the latter to normal position while key lever is in depressed position, means restoring said coupling to normal operative position upon release of the key lever.

16. In a recoil mechanism for a type key, a type bar, a key lever, actuating means at all times operatively connecting the key

lever and the type bar comprising a backward pull link, a vertically disposed vibratory lever, an upward curved draw link, and a thrust link moving the type bar to printing point upon depression of the key lever, means reversely breaking said coupling after the printing impact of the type bar, an angle top trippet plate pivoted intermediately of its ends to the side of the key lever, an upward projection provided by the rear end of said trippet plate with a plurality of holes therein, a return spring supported by the upward curved draw link and trippet plate moving in opposition to the tension thereof returning the type bar to normal position while key lever is in depressed position, means restoring said mechanism to normal operative position upon release of the key lever.

17. In a mechanical movement for a typewriter machine key, a key lever, a type bar, elements connecting said key lever and type bar comprising a backward pull link, a vertically disposed vibratory lever, a trip link coupling composed of an upward curved draw link and a thrust link, normal operative position of the elements of said coupling being folded moving the type bar to printing point upon depression of the key lever, elements of said coupling unfolding reversely breaking said connection after the printing impact of the type bar returning the latter to normal position while key lever is in depressed position, means restoring the elements of said coupling to normally folded position upon the release of the key lever.

18. In a type key mechanism, a type bar, a key lever, means connecting the type bar and key lever comprising a vertically disposed vibratory lever, a backward pull link operatively connecting the vibratory lever and type bar, a trip link coupling comprising an upward curved draw link and a thrust link, a forward border pivot operatively connecting the draw link and thrust link, a backward border pivot operatively connecting said draw link and vibratory lever, an interior pivot operatively connecting the key lever and thrust link operating in a plane between said forward border pivot and backward border pivot above a reversely breaking line drawn through said backward border pivot and forward border pivot operatively interlocking said coupling moving the type bar to printing point upon depression of the key lever, means actuating said thrust link downwardly moving said interior pivot below said reversely breaking line drawn through the forward border pivot and backward border pivot reversely breaking said coupling after printing impact of the type bar for returning the latter to normal position while the key lever is in depressed position, means actuating said thrust link upwardly moving said interior pivot above the

reversely breaking line drawn through the forward border pivot and backward border pivot restoring said coupling to normal operative position upon release of the key lever.

5 19. In an automatic recoil mechanism for a typewriter key, a type bar, a key lever having an upward projection, a vertically disposed vibratory lever, a backward pull link operatively connecting the vibratory lever 10 and type bar, a trip hook coupling comprising an upward curved draw link and a thrust link operatively connecting the vibratory lever and key lever moving the type bar to printing point upon depression of the key 15 lever, an angle top trippet plate operatively pivoted at the side of the key lever in the rear of said upward projection of the key lever—said angle top of the trippet plate riding the upper edge of the key lever stopping the movement of the trippet plate at its 20

normal position, a trip hammer wider than the key lever provided by the front end of the angle top trippet plate, a trip rod extending laterally across the machine under the key lever communicating with the lower edge 25 of said angle top trippet plate limiting the downward movement of said trip hammer upon depression of the key lever, upper edge of said trip hammer communicating with said thrust link reversely breaking said coupling automatically returning the type bar to normal position without printing impact upon slow depression of the key lever, means restoring said mechanism to normal operative position upon release of the key 30 lever.

Signed at Fort Collins, in the county of Larimer, and in the State of Colorado this 30th day of April, A. D. 1925.

ORVILLE U. DESHA.
